COMPRESSOR

Harry A. Feldbush, Short Hills, N. J., assignor to
Worthington Pump and Machinery Corporation,
Harrison, N. J., a corporation of Delaware

Application March 15, 1939, Serial No. 261,882

1 Claim. (Cl. 230—293)

This invention relates to compressors and more particularly to a compressor for use in a refrigerating system for handling a refrigerant such as "Freon," ammonia, etc. In compressors handling a refrigerant such as "Freon" or the like it is extremely difficult if not impossible to prevent the leakage of the refrigerant from the cylinder along the piston rod, particularly since such refrigerants are soluble in lubricating oil. The refrigerant leakage being subjected to atmospheric pressure when it leaves the compressor cylinder immediately becomes gas and escapes, being unrecoverable and resulting in loss of refrigerant as well as in some instances causing an undesirable odor and pollution of the air in the compressor room. Since the loss of the refrigerant due to such leakage, over an extended period, is considerable, it is desirable from an economical standpoint to prevent the dissipation of such refrigerant and return it to the refrigerating system.

It is an object of the present invention to provide a method and apparatus whereby the leakage of refrigerant from a compressor to atmosphere and its resultant dissipation will be prevented, and the leakage refrigerant will be returned to the system.

More specifically, an object of the present invention is to provide in combination with a refrigerant compressor having a completely enclosed crank case in substantially fluid-tight connection with the compressor cylinder or cylinders which crank case receives the refrigerant leaking from the cylinders along the piston rods, an evacuating compressor having its suction connected to the crank case and its discharge to the refrigerant system for maintaining pressure in the crank case at approximately atmospheric pressure for recovering the vaporous or gaseous refrigerant from the crank case and returning it to the system in which the refrigerant compressor is employed.

With these and other objects in view, as may appear from the accompanying specification, the invention consists of various features of construction and combination of parts, which will be first described in connection with the accompanying drawings, showing a compressor of the preferred form embodying the invention, and the features forming the invention will be specifically pointed out in the claim.

In the drawings:

Figure 1 is a vertical section through a double-acting refrigerant compressor constructed in accordance with the present invention and showing

the evacuating compressor connected in the system.

Figure 2 is a vertical section taken on the line 2—2 through a compressor constructed in accordance with the present invention.

Referring more particularly to the drawings, a duplex double-acting compressor for compressing "Freon," ammonia or analogous refrigerants is shown in Figures 1 and 2 of the drawings, and comprises the cylinder block 1 having the compound cylinders 2 and 3 formed therein, in which the pistons 4 reciprocate. The pistons 4 have piston rods 5 connected thereto which extend through suitable packings 6 into the crank case 7, where they are connected to cross-heads 8. The cross-heads 8 reciprocate on the guides 9 and are connected by connecting rods 10 to the crank shaft 11. The crank shaft 11 rotates in suitable bearings 12 and 14, carried by the crank case 15 of the compressor. The crank case 15 is connected in fluid-tight connection, as shown at 16, to the cylinder block 1, and the space in the interior of the crank case is reduced to the minimum necessary for the effective operation of the parts of the compressor therein by suitable webbing, as shown at 17. In the present system it is desirable to have as small a space as possible within the crank case of the compressor, since this space is evacuated by a relatively small evacuating compressor 18. The suction of the evacuating compressor 18 is connected by means of a pipe 19 to the interior of the crank case 15, while its discharge is connected by means of a suitable pipe 20 either to the suction of the low pressure end of the low pressure cylinder of the compressor or to other suitable low pressure points in the refrigerating system in which the compressor is employed. A check valve 21 is positioned in the pipe 20 to prevent back-flow to the evacuating compressor 18.

A pressure actuated electric switch 22 of any approved type, which may be purchased upon the open market, is placed in the pipe 19 so that when the pressure in the crank case 15 reaches a predetermined height the motor 23 which operates the evacuating compressor 18 will be started for operating the evacuating compressor to evacuate the interior of the crank case 15, or in other words, from the crank case 15 all of the refrigerant which has leaked into this crank case along the piston rods 5, and at the same time to maintain a pressure within the crank case of approximately atmospheric pressure so that the refrigerant will be in a gaseous form in the crank case and consequently become separated from the lu-

bricating oil on the piston rods, which lubricating oil has served as a carrier to carry the refrigerant absorbed thereby into the crank case. When the pressure within the crank case falls below a predetermined low pressure the pressure actuated switch structure 22 will operate to cut off the motor 23 and stop the operation of the evacuating compressor 18. The pipe 19 may be connected to the interior of the crank case 15 at any convenient point.

In Figure 1 of the drawings a branch pipe 24 is shown connected to the pipe 19 between the hand operated shut-off valve 25 and the evacuating compressor 18 so that if it is desired the valve 25 may be closed and the valve 26 in the branch pipe 24 opened, causing the evacuating compressor 18 to draw its suction through the branch pipe 24. The branch pipe 24 is connected through a suitable duct 27 with a space within the packing 28 for the crank shaft 11, which space is identified by the lantern gland 29. The evacuating compressor 18 drawing its suction through the packing 28 and passage 27 will draw the refrigerant through the packing or along the crank shaft 11 and thus to the evacuating compressor and back into the refrigerant system. If it is so desired, both of the valves 25 and 26 may be opened so that the compressor 18 will draw from both sources.

By maintaining a pressure in the fluid tight crank case and within the bearing 14 of approximately atmospheric pressure the refrigerant which leaks into the crank case will remain in a gaseous state and will become separated from the lubricating oil so that it may be readily with-

drawn by the evacuating compressor 18 and returned to the refrigerating system, thus not only preventing its escape into the compressor room, but also resulting in the saving of the refrigerant, some types of which are quite expensive.

It will be understood that the invention is not to be limited to the specific construction or arrangement of parts shown, but that they may be widely modified within the invention defined by the claim.

What is claimed is:

In a refrigerant compressor, the combination with a compressor cylinder, a piston and an operating shaft for said piston, of a sealed crank case in fluid tight connection with the cylinder for receiving refrigerant leakage therefrom, said shaft extending out of said crank case, a packing about said shaft, an evacuating compressor operable independently of the refrigerant compressor and having its suction connected to said packing structure to withdraw refrigerant leakage from the packing and reduce the pressure within said packing structure about the shaft to approximately atmospheric pressure for preventing leakage of refrigerant through the packing structure, means connecting the suction of said evacuating compressor to the interior of said crank case for withdrawing gaseous refrigerant from the crank case, and pressure actuated means actuated by pressure from within said crank case for controlling operation of said evacuating compressor independently of operation of the refrigerant compressor.

HARRY A. FELDBUSH.
